HIGH FREQUENCY ANTENNA SYSTEM

Laurence M. Leeds, Rotterdam Junction, and
 Marvel W. Scheldorf, Schenectady, N. Y., as-
 signors to General Electric Company, a corpo-
 ration of New York

Application November 15, 1941, Serial No. 419,234

12 Claims. (Cl. 250—11)

Our invention relates to a high-frequency antenna system and particularly to a high-frequency directive antenna suitable for operation on horizontally polarized waves.

In broadcasting radio programs within the higher frequency channels, for example within the channels allotted at present by the Federal Communications Commission to frequency modulation service, it is generally desirable to distribute the energy radiated from the transmitting antenna as uniformly as possible in all horizontal directions. At the same time it is desirable to concentrate the radiated energy at low angles in the vertical plane. In other words, for most effective service, the radiating system should have a high degree of vertical directivity and the horizontal field strength pattern should be as nearly circular as possible. It is also generally advantageous to polarize the transmitted waves horizontally rather than vertically for technical reasons familiar to those skilled in the art. Accordingly, it is an important object of our invention to provide an improved high-frequency antenna which possesses these and other desirable electrical characteristics.

In general, simple two-terminal antennas heretofore known have possessed non-uniform radiation characteristics in the plane of polarization. Accordingly, it has heretofore been thought necessary to resort to compound antenna arrangements in order to secure a reasonably uniform horizontal wave pattern with horizontal polarization. Compound arrangements are obviously more expensive and more difficult to adjust than the simpler radiating structures. For example, as the array becomes more complex, from the electrical standpoint it becomes increasingly difficult to adjust the operating frequency, to match the impedances to the various circuit elements properly, and to secure the correct phase relationships between the currents in the active radiating elements. Furthermore, from the mechanical standpoint it becomes increasingly difficult to provide the necessary support and insulation for the radiators and transmission feed lines and to secure a strong, rigid construction capable of withstanding the weather conditions likely to be encountered in actual service. Accordingly, it is a further object of our invention to provide an improved and simplified antenna structure, capable of producing a substantially uniform radiation pattern in the plane of polarization, which is more economical to build and easier to adjust than prior art systems possessing comparable radiation characteristics.

It is particularly an object of our invention to provide an improved and simplified antenna structure which has only two connection terminals and which nevertheless provides a substantially circular radiation pattern in the plane of polarization.

Still another object of our invention is to provide an improved high-frequency directive antenna which possesses these desirable characteristics and which, in addition, can be readily adjusted to any operating frequency within a wide range of frequencies without changing the physical dimensions of the active radiating elements.

Another object of our invention is to provide an improved high-frequency antenna system incorporating means for adjusting its feeding point impedance nearly independently of its natural frequency, within reasonable limits, without changing the physical dimensions of the active radiating elements.

The features of our invention which we believe to be novel are set forth with particularity in the appended claims. Our invention itself, however, together with further objects and advantages thereof, may best be understood by reference to the following description taken in connection with the accompanying drawing, in which Figs. 1a, 1b and 2 are schematic diagrams illustrating certain principles underlying the present invention; Fig. 3 is a perspective view, partly schematic, of a transmitting or receiving system incorporating a practical antenna structure embodying the invention; Fig. 4 is an enlarged fragmentary side elevation showing a modified construction at the transmission line feed point connections of the antenna of Fig. 3; Figs. 5, 6a, 6b and 7 are graphs and schematic diagrams illustrating certain electrical characteristics of antennas constructed in accordance with the invention; and Fig. 8 is a schematic perspective view of a compound antenna array having four unit sections constructed in accordance with the invention.

Our invention will be better understood if a few fundamental principles of antenna operation are first reviewed briefly. Assume that the linear dipole antenna 10 in Fig. 1a is fed with high-frequency current from a suitable source, not shown, through a transmission line 11. The instantaneous currents in the antenna and transmission line are conveniently indicated by the small arrows. It is well known that if the dipole 10 is electrically one-half wave long at the operating frequency and if no capacity exists between its free ends, then the current distribution along the dipole is sinusoidal essentially and that the

current is maximum at its midpoint and zero at its ends. Such a current distribution is indicated by the dashed curve 12.

Assume next that capacity exists between the free ends of the dipole, as indicated by the capacity plates 13 and 14 at the ends of dipole 15 in Fig. 1b. Also assume that the dipole 15 is physically shorter than a half wave length by an amount such that the effective electrical length of the entire system is equal to one-half wave length. It is well known that the current at the free ends of the dipole is not zero, as in the case of Fig. 1a, but has some finite value. The dashed curve 16 indicates the current distribution along dipole 15 for a certain value of end capacity. It will be observed that the current distribution along dipole 15 is more uniform than in the case of dipole 10.

Assume next that the dipole 15 of Fig. 1b is formed into a planar loop with its free ends closely spaced in terms of the operating wave length. Such a structure is represented by the dipole 17 in Fig. 2, the capacity between its free ends being represented by the capacity C_1 . In accordance with our invention, this capacity is preferably made adjustable or variable for reasons that will shortly become apparent. Furthermore, it is sometimes desirable to provide a variable capacity C_2 across the feed point connections 18. The function of this capacity C_2 will also be considered at a subsequent point in this specification.

The instantaneous currents in the system of Fig. 2 are represented by arrows, in the same manner as in Figs. 1a and 1b, and the current distribution for one value of C_1 is represented by the dashed curve 19 (assuming that the effective length of the antenna, including the effect of the capacities C_1 and C_2 , is one-half wave length).

It will now be apparent that the dipole 17 and the capacities C_1 and C_2 in Fig. 2 provide a closed current loop for the high-frequency currents flowing in the system. In accordance with our invention the dipole 17 is always made shorter than a half wave length of the operating frequency, both physically and electrically, but the entire loop is made to appear equal to a half wave antenna at the feed points 18 through adjustment of C_1 and C_2 . The field strength pattern in the plane of polarization, i. e., in the plane of the loop, is always symmetrical. It has a maximum value along the axis A—A and a minimum value along the axis B—B. For the theoretical case where the capacity C_1 is equal to zero, the ratio of the field strength along the axis A—A to the field strength along the axis B—B would be approximately equal to 1.4. However, in the system of Fig. 2 the capacity C_1 simultaneously performs two important functions: (1) It controls the current distribution in the active radiator 17 as previously described, and (2) it determines the natural frequency of the system for any given physical dimensions of the loop and for any fixed value of C_2 . As the capacity C_1 is increased, the current distribution, and consequently the radiation pattern in the plane of the loop, approach a circle, which is highly advantageous for high frequency broadcast service. Furthermore, for the same physical dimensions of the loop the larger the capacity C_1 , the longer is the effective electrical length of the system and the lower its natural frequency.

As the capacity C_1 is increased, the radiation resistance of the system is decreased. Conse-

quently, the feeding point impedance, which is proportional to radiation resistance, is likewise decreased. For example, in a practical embodiment of the simple antenna schematically represented in Fig. 2 the impedance looking into the terminals 18 may be only of the order of four to ten ohms. As a practical matter it is difficult to secure a correct impedance match between such an antenna and a transmission line of reasonable dimensions. However, this disadvantage can be obviated and additional advantages, both electrical and mechanical, can be secured by utilizing a form of antenna construction shown in Fig. 3 and now to be described.

The active radiating elements in the system shown in Fig. 3 comprise two dipoles 20 and 21 each of which is formed into the arc of a circle. The circles through the center lines of these dipoles are of substantially equal diameters. The dipoles 20 and 21 are positioned in substantially parallel relationship and are similarly oriented with respect to a common vertical axis C—C. In this particular embodiment, the dipoles lie in adjacent horizontal planes which are closely spaced in terms of the operating wave length of the system.

The lower dipole 21 is opened at its center to provide suitable terminal connections 22 and 23. Any suitable form of transmission line 24 known to the art may be utilized to effect transfer of energy between the feed connections 22 and 23 and high-frequency radio apparatus, represented only schematically by the box 25. In order to simplify the drawings, the transmission line 24 has been represented as an open-wire line. In actual practice it may be preferable to use a concentric transmission line provided with suitable means for effecting transition from unbalanced to balanced condition; or in some cases it may be preferable to employ two concentric lines in balanced connection. It is believed that the details of these and other suitable transmission line structures will be readily apparent to those skilled in the art. They have been mentioned only briefly for the sake of completeness.

The corresponding free ends of the dipoles 20 and 21 are conductively connected together by the metallic members 26 and 27. While it will be understood that any suitable mechanical construction thus far described, the dipoles 20 and 21 are preferably in the form of large tubular metal conductors, or hollow pipes, of relatively low electrical resistance. The connecting members 26 and 27 are preferably in the form of rectangular metal straps or blocks, as shown, which are suitably bonded to the corresponding ends of the conductors 20 and 21, as by welding, brazing, soldering, or the like, in order to form a strong, unitary mechanical structure.

The antenna system of Fig. 3 is supported at a single point, surrounding a vertical supporting pole or mast 28, by means of a radial member 29. The member 29 is rigidly secured to the supporting pole 28 at one end and to the mid-point of the upper dipole 20 at the other end. Both the supporting member 29 and the pole 28 are preferably of tubular metal construction. The mast 28 is preferably grounded to protect the transmission line 24 and high frequency apparatus 25 against damage by lightning. The member 29 does not disturb the electrical performance of the system because the antenna current is a maximum at this point and the voltage a mini-

imum when the system is correctly adjusted to the operating frequency.

U-shaped plates 30 and 31 are respectively fitted over the opposing faces of the blocks 26 and 27 in order to provide adjustable capacity surfaces between the ends of the dipoles 20 and 21. As shown, each of the plates is provided with a plurality of slots registering with screws threaded into the blocks 26 and 27. It will thus be apparent that the capacity between the plates may be adjusted by loosening the screws and moving the plates toward or away from each other. Of course any other suitable mechanical means may optionally be employed for varying or adjusting the effective capacity between the ends of the dipoles 20 and 21.

It will be recognized that the antenna structure of Fig. 3 resembles an antenna structure known to the art as a folded dipole, having its two arms bent into the arc of a circle and provided with capacity plates 30 and 31 between its ends. The electrical characteristics of the folded dipole, in its usual linear form, are familiar to those skilled in the art of antenna design. Briefly, the radiation characteristics of a folded dipole do not differ substantially from the characteristics of a simple dipole of the same electrical length. The current distribution is approximately sinusoidal and the radiation pattern is essentially the same as the pattern produced by the simple dipole. Therefore, the system of Fig. 3 may be compared with the simplified system of Fig. 2, the pair of dipoles 20 and 21 corresponding to the dipole 17, and the capacitor 30, 31 corresponding to the capacity C_1 . However, by employing the folded type of dipole the principal disadvantage inherent in the system of Fig. 2, i. e., the low feeding point impedance, is overcome.

The folded dipole performs the dual function of a radiator and an impedance matching transformer. The feeding point impedance presented to the transmission line by the folded dipole depends primarily upon the number of individual sections connected together and upon their physical dimensions. In the case of a folded dipole having a plurality of sections of equal diameter the feeding point impedance is approximately equal to the impedance of one section alone multiplied by the square of the number of sections. Furthermore, the transformation ratio may be varied within limits by the use of conductors of unequal diameters as components of the radiating element. Thus in the system illustrated in Fig. 3 the diameter of the conductor 20 is represented as being approximately twice the diameter of the conductor 21. In a practical construction of the two-section antenna represented in Fig. 3 the feeding point impedance was somewhat greater than four times the impedance of one of the dipoles 20 or 21 alone, i. e., of the order of about 35 ohms. It is a relatively simple matter to match such an impedance to that of the transmission line. It will also be apparent in view of the foregoing that a higher terminal impedance can have been secured by employing three or more closely spaced sections in the folded dipole construction, i. e., by adding one or more additional horizontal conducting loops with ends terminating at the connecting blocks 26 and 27.

The radiation characteristics of the system of Fig. 3 are not substantially different from those of the system of Fig. 2 previously discussed. If the peripheral length of the active antenna were

physically equal to one-half wave length, the diameter of the loop would of course be theoretically equal to about .159 times the wave length. However, as previously explained, due to the end capacity C_1 between the plates 30 and 31, these values are actually somewhat less. For example, in the practical embodiment of the invention previously referred to, the active radiating element, comprising the dipoles 20 and 21, was roughly one-third of a wave length long and the loop diameter was consequently of the order of one-tenth of a wave length.

By varying the capacity C_1 it is possible to vary the resonant frequency of the system over a very wide range relative to its mean operating frequency. For example, Fig. 5 shows experimental reactance and resistance variation curves for an antenna similar to that of Fig. 3 except for the fact that both sections 20 and 21 were of the same diameter. The curves X_1 and R_1 show the reactance and resistance variations with frequency when the direct capacity between the plates 30 and 31 was about 20 micro-microfarads. It will be observed that the resonant frequency f_1 of the system for this adjustment was about 39 megacycles. Similarly, the curves X_2 and R_2 show the reactance and resistance variations with frequency when the direct capacity between these plates was about 12 micro-microfarads. In this case it will be observed that the resonant frequency f_2 of the system was about 45 megacycles. In this particular system it was also possible to vary the resonant frequency to somewhat higher values and to very much lower values, had this been desired. However, these curves illustrate that it is entirely practicable to operate an antenna system of this type, without changing the physical dimensions of the active radiating elements, at any frequency within the range which includes the present channels allotted to frequency modulation service, i. e., about 42-50 megacycles.

The curves of Fig. 5 also show that the radiation resistance of the system decreases as the resonant frequency is lowered by decreasing the spacing between the plates 30 and 31. As previously described in connection with Fig. 2, variations in the current distribution, the horizontal field pattern and the input impedance also necessarily occur at the same time. However, as a further refinement of our invention, the feeding point impedance of the system may be varied substantially independently of the radiation resistance of the antenna, within reasonable limits, so as to offset this effect in a manner now to be described.

The curves X_1 and X_2 of Fig. 5 indicate that the input reactance of this type of antenna varies rapidly with frequency. Therefore, conversely, a considerable reactance change is associated with a small change in the radiation resistance and natural frequency of the antenna. By virtue of this fact the feeding point impedance can be varied, within limits, by variation of a shunt capacity across the input terminals of the system without seriously affecting the natural frequency. Such a capacity C_2 is schematically represented in Fig. 2. Fig. 4 illustrates one practical way to provide such capacity variations between the terminal connections 22 and 23 of the antenna of Fig. 3. Corresponding reference numerals have been applied to corresponding elements in the two figures. The necessary capacity is provided between the flat disks 35 and 36 carried by shafts 37 and 38 threaded into the two arms of the dipole 21.

The spacing between the disks may readily be adjusted by loosening one or both of the clamping nuts 39 and 40 and rotating the capacitor plate assembly. It will of course be obvious that other equivalent mechanical structures may alternatively be employed to provide the necessary capacity variation.

The addition of the capacity C_2 across the input terminals of the system results in the equivalent electrical network represented in Fig. 6a where R_a , L_a and C_a respectively represent the series resistance, series inductance, and series capacitance of the antenna alone. This network may further be simplified to the form shown in Fig. 6b where R' , L' and C' respectively represent the equivalent series resistance, series inductance, and series capacitance of the entire system including C_2 . As C_2 is increased from low values, the equivalent series network resistance R' is caused to increase up to a limiting value equal to twice the actual antenna resistance R_a , without any serious change in the natural frequency of the system. The natural frequency of the system is easily readjusted to its previous value by readjustment of capacity C_1 . The curve of Fig. 7, which was prepared from theoretical considerations, shows how the ratio of R_1 to R_a varies with change in C_2 . As C_2 is increased, the ratio R' to R_a increases up to a limiting value of 2, corresponding to the maximum value which still permits a resonant condition in the antenna circuit.

The portions of the curve of Fig. 7 having a negative slope show that the same values of C_2 may be used to give an equivalent network resistance R' much greater than $2R_a$. These conditions are equivalent to shunt resonance in the system. Thus for a given value of C_2 , for example as indicated by the dashed line 50 in Fig. 7, the point 51 corresponds to the resonant frequency of the system for equivalent series resonance and the point 52 corresponds to the resonant frequency of the system for equivalent shunt resonance. However, in the latter case a variation in C_2 produces a very much greater change in the natural frequency. Therefore the system should always be operated in the range of equivalent series resonance to prevent material variation in the resonant frequency of the system as C_2 is varied.

In order to secure greater vertical directivity and greater gain in the horizontal plane, a plurality of antenna units may be arranged in a tier, spaced apart equally along a common vertical axis. Such a compound antenna array having four unit sections 60, 61, 62, and 63 constructed in accordance with the invention is schematically represented in Fig. 8. The units are supported in any suitable manner, not shown, preferably by a single central mast extending along the axis D—D of the system in the same manner as the antenna of Fig. 3. For maximum directivity in the horizontal plane, the vertical spacing between the adjacent sections is proportioned in accordance with the principles set forth in Patent 2,254,697, Sidney Godet, assigned to the same assignee as the present invention. It so happens that for this particular type of antenna system, the optimum spacing between units for maximum directivity in the horizontal plane is very close to one wave length. Accordingly, where the power required to be radiated from the system is not too high, all of the units may be cophasally energized from the high frequency apparatus 70 through a common transmission line structure in the manner shown in Fig. 8. A

balanced feed is provided by the two concentric transmission lines 84 and 85. By employing quarter wave matching sections 86, 87, 88, and 89 between the respective antenna units and the transmission feed lines, the total impedance presented to the transmission line by each unit may be increased to reasonable values. For compound arrays operating at high power it will generally be preferable to employ a plurality of separate transmission lines from each unit antenna to a common junction box, as will readily be appreciated by those skilled in the art.

The foregoing description has shown that antenna structures embodying our invention possess many advantages, both electrical and mechanical, over prior art systems. Many other advantages are also secured. These antennas are dimensionally smaller than prior art structures of similar radiation characteristics, present less area for wind load and have a pleasing appearance. They are also readily adapted to sleet and ice melting equipment, since heating elements may be included within the radiators and connections may be made through the grounded tubular mast and radial support. By employing a solid dielectric material between the plates of the capacitors C_1 and C_2 , the system can be made relatively insensitive to the effects of rain, snow, and sleet, which otherwise tend to vary the resonant frequency by causing variations in C_1 and C_2 .

It has heretofore been proposed to use a pair of horizontal half-wave dipoles, crossed at right angles and energized in phase quadrature, in order to secure a substantially circular radiation pattern in the horizontal plane. The antenna of Fig. 3 has reduced radiation in directions above and below the horizontal plane, and consequently greater field strength in the horizontal plane for a given power input, as compared to this prior art antenna. Furthermore, in a compound array embodying our invention, such as is shown in Fig. 8, the antenna units are necessarily more widely spaced for optimum directivity in the horizontal plane, because of the increased horizontal directivity of the individual units. Consequently, since there is less coupling between units, the adjustment of the individual units in the array is simplified.

Although our invention finds particular application in a transmitting antenna system, and although the foregoing specification has been presented with emphasis on that fact, it will of course be apparent that our improved antenna system may be employed with receiving equipment. The fact that the directivity, current distribution and other characteristics of a particular antenna are substantially the same whether it is employed to abstract energy from an incident high frequency electromagnetic wave or to radiate such a wave is so well known as to require no elaboration.

It will also be apparent that, while we have shown and described what we believe to be preferred embodiments of our invention, many other modifications will readily suggest themselves to those skilled in the art. For example, the active radiating element need not be in the shape of a circle, although this form is preferred because of its pleasing appearance and simple construction. The essential requirement in this respect is that the antenna comprises a peripherally incomplete conducting loop enclosing a substantial area and having its free ends positioned in closely spaced capacitive relationship. The radiation

pattern produced by a loop in the form of a square or other similar polygon differs only very slightly from that of the circular loop. Also, while the dipoles 28 and 29 have been represented in Fig. 3 as being positioned one above the other, the electrical characteristics of the system are not substantially different if the dipoles have slightly different diameters and are both positioned in the same horizontal plane so long as they lie on substantially parallel curves and are closely spaced from each other in terms of the operating wave length. We therefore contemplate by the appended claims to cover any such modifications as fall within the true spirit and scope of our invention.

What we claim as new and desire to secure by Letters Patent of the United States, is:

1. A high frequency antenna system comprising a plurality of closely spaced, separated conductors similarly oriented and connected together at their corresponding ends and forming a peripherally incomplete loop, the ends of said loop being closely spaced and terminating in means providing substantial capacity therebetween, one of said conductors being coupled to a transmission line for transfer of high frequency energy between said loop and said line, said system having an effective electrical length substantially equal to one-half wave length at said high frequency.

2. A high-frequency directive antenna system adapted to be tuned to any frequency within a relatively wide range of operating frequencies comprising a plurality of closely spaced, separated conductors similarly oriented and connected together at their corresponding ends and forming a peripherally incomplete loop, the ends of said loop being closely spaced and terminating in means providing substantial capacity therebetween, one of said conductors being coupled to a transmission line for transfer of high-frequency energy between said loop and said line, said loop being physically shorter than one-half wave length at frequencies within said range, and means for varying said capacity, thereby to adjust said antenna to resonance at any desired frequency within said range.

3. A high-frequency directive antenna system adapted to be tuned to any frequency within a relatively wide range of operating frequencies comprising a plurality of conductors each in the shape of a peripherally incomplete planar loop, said conductors being positioned in substantially parallel relationship and closely spaced from each other, a pair of capacity surfaces, one end of each conductor being connected to one of said surfaces and the other end of each conductor being connected to the other of said surfaces, said conductors being physically shorter than a half wave length at frequencies within said range, a transmission line coupled to one of said conductors at its midpoint, and means for varying the effective spacing between said surfaces, thereby to adjust said antenna to resonance at any desired frequency within said range.

4. A high-frequency directive antenna system comprising a plurality of closely spaced, separated conductors similarly oriented and connected together at their corresponding ends and forming a peripherally incomplete loop, the ends of said loop being closely spaced and terminating in means providing substantial capacity therebetween, one of said conductors also being open at an intermediate point to provide a pair of ter-

minals, a transmission line connected to said terminals for transfer of high frequency energy between said loop and said line, and means for varying the terminal impedance presented to said line by said system, said last means comprising a variable capacitor connected between said terminals, said system being adjusted to have an effective electrical length substantially equal to one-half wave length at said high frequency.

5. A high-frequency directive antenna system adapted to be tuned to any frequency within a relatively wide range of operating frequencies comprising a plurality of closely spaced substantially parallel dipoles connected together at their corresponding ends and forming a peripherally incomplete loop, the ends of said loop being closely spaced and terminating in variable capacity means, one of said dipoles also being open at its midpoint to provide a pair of terminals, a transmission line connected to said terminals for transfer of high-frequency energy between said loop and said line, said loop being physically shorter than one-half wave length at frequencies within said range, and second means providing variable capacity between said terminals, whereby through adjustments of said variable capacity means, said system may be adjusted to be resonant at any desired frequency within said range and to have a predetermined terminal impedance at said desired frequency.

6. A directive antenna system for operation at a high frequency comprising a plurality of dipoles each in the shape of a peripherally incomplete planar loop, said dipoles being positioned in substantially parallel relationship and closely spaced from each other in terms of a wave length at said high frequency, a pair of capacity surfaces closely spaced from each other in terms of said wave length, one end of each dipole being conductively connected to one of said surfaces and the other end of each dipole being conductively connected to the other of said surfaces, said dipoles being physically shorter than a half wave length at said frequency, and a transmission line electrically coupled to one of said dipoles.

7. A high frequency directive antenna system for radiating horizontally polarized waves comprising a plurality of closely spaced, substantially parallel conductors connected together at their corresponding ends and forming a peripherally incomplete horizontal loop, the ends of said loop terminating in a pair of surfaces having substantial capacity therebetween, a source of high frequency energy, means for energizing said loop from said source comprising a transmission line electrically coupled to one of said conductors at its midpoint, said system having an effective electrical length substantially equal to one-half wave length at the operating frequency, the configuration of said loop and the value of said capacity being so proportioned that the horizontal field strength pattern produced by said system approaches a circle.

8. A high frequency directive antenna system comprising a plurality of closely spaced, separated conductors similarly oriented and connected together at their corresponding ends and forming a peripherally incomplete loop, the ends of said loop being closely spaced and terminating in means providing substantial capacity therebetween, one of said conductors having center feed terminals connected to a transmission line for transfer of high frequency energy between said loop and said line, said system

having an effective electrical length substantially equal to one-half wave length at said high frequency, and means for supporting said system at a single point comprising a conductive supporting member attached to another of said conductors at its center.

9. A high frequency directive antenna system comprising a plurality of closely spaced, separated conductors similarly oriented and connected together at their corresponding ends and forming a peripherally incomplete horizontal loop, the ends of said loop being closely spaced and connected to the opposite sides of a variable capacitor, one of said conductors being open at its midpoint to provide a pair of terminals, a transmission line connected to said terminals, a second variable capacitor connected between said terminals, said loop being physically shorter than a half wave length at the operating frequency of the system and tuned to resonance at said frequency by adjustments of said capacitors, and a conducting supporting for said system attached to another of said conductors at its midpoint.

10. A transmitting antenna for radiating horizontally polarized high-frequency waves substantially uniformly in all horizontal directions comprising, in combination, a plurality of substantially circular horizontal radiators, said radiators being circumferentially incomplete, similarly oriented with respect to a common vertical axis and closely spaced from each other in terms of the operating wave length, said radiators being connected together at one end by a first capacity plate and at the other end by a second capacity plate which is closely adjacent to said first plate, one of said radiators also being open at its midpoint, a transmission feed line connected to said midpoint, said radiators being physically shorter than a half wave length at said frequency, and means for adjusting said antenna to resonance at said frequency comprising means to adjust the capacity between said plates.

11. A transmitting antenna for radiating horizontally polarized high frequency waves substan-

tially uniformly in all horizontal directions comprising in combination a plurality of radiators lying substantially in the arcs of concentric horizontal circles, said radiators being closely spaced from each other and similarly oriented about the common vertical axis, said radiators being connected together at one end by a first capacity plate and at the other end by a second capacity plate which is closely adjacent to said first plate, a transmission line adapted to supply current of a high frequency from a source to said antenna, one of said radiators having center feed terminals connected to said transmission line, said radiators being physically shorter than a half wave length at said high frequency, and means for adjusting said antenna to resonance at said frequency comprising means to adjust the capacity between said plates.

12. A high frequency directive antenna system for radiating horizontally polarized waves comprising a plurality of radiators lying substantially in the arcs of concentric horizontal circles, said radiators being closely spaced from each other and similarly oriented about the common vertical axis, a variable capacitor having a pair of plates, one end of each radiator terminating in a connection to one of said plates and the other end of each radiator terminating in a connection to the other of said plates, one of said radiators being open at its center to provide a pair of input terminals, a transmission feed line connected to said terminals, a second variable capacitor connected across said terminals, said radiators being physically shorter than a half wave length at the operating frequency of the system and tuned to resonance at said frequency by adjustments of said variable capacitors, and a single point support for said system comprising a conductive supporting member attached to another of said radiators at its midpoint.
